UNITED STATES PATENT OFFICE

ROBERT NELSON ROYLE, OF OSSINING, NEW YORK

DESIGN FOR A BOOKMARK

Application filed October 5, 1932. Serial No. 45,222. Term of patent 7 years.

To all whom it may concern:

Be it known that I, ROBERT NELSON ROYLE, a citizen of the United States, residing at Ossining, in the county of Westchester and State of New York, have invented a new, original, and ornamental Design for a Bookmark, of which the following is a specification, reference being had to the accompanying drawing, forming part thereof.

I claim:

The ornamental design for a bookmark, as shown.

ROBERT NELSON ROYLE.
